(57) **CLAIM**

The ornamental design for a cap with cork as shown and described.

DESCRIPTION

FIG. 1 is a top perspective view of a first embodiment of a cap with cork;

FIG. 2 is a bottom perspective view thereof;

FIG. 3 is a side elevational view thereof, the other side views being identical;

FIG. 4 is a top plan view thereof;

FIG. 5 is a bottom plan view thereof;

FIG. 6 is a top perspective view of a second embodiment of a cap with cork;

FIG. 7 is a bottom perspective view thereof;

FIG. 8 is a side elevational view thereof, the other side views being identical;

FIG. 9 is a top plan view thereof;

FIG. 10 is a bottom plan view thereof;

FIG. 11 is a top perspective view of a third embodiment of a cap with cork;

FIG. 12 is a bottom perspective view thereof;

FIG. 13 is a side elevational view thereof, the other side views being identical;

FIG. 14 is a top plan view thereof; and,

FIG. 15 is a bottom plan view thereof.

The broken lines in the drawings depict portions of the cap with cork that form no part of the claimed design. The dot-dash broken lines represent the boundaries of the claim and form no part thereof.
